UNITED STATES PATENT OFFICE

EARL C. BOOTH, OF INDIANAPOLIS, INDIANA

DESIGN FOR AN ELECTRIC HEATER

Application filed October 27, 1930. Serial No. 37,394. Term of patent 7 years.

To all whom it may concern:

Be it known that I, EARL C. BOOTH, a citizen of the United States, residing at Indianapolis, in the county of Marion and State of Indiana, have invented a new, original, and ornamental Design for an Electric Heater, of which the following is a specification, reference being had to the accompanying drawings, forming part thereof.

In the drawings, Figs. 1 and 2 are front and side elevations respectively of a heater embodying my new design.

The rear face of the heater is substantially plain.

I claim:

The ornamental design for an electric heater, as shown and described.

In witness whereof, I have hereunto set my hand at Indianapolis, Indiana, this 23d day of October, A. D. on thousand nine hundred and thirty.

EARL C. BOOTH.
